UNITED STATES PATENT OFFICE.

LOUIS J. BALTZ, OF BUFFALO, NEW YORK.

SUCTION-TUBE FOR HYDRAULIC DREDGING-MACHINES.

1,027,095.

Specification of Letters Patent. Patented May 21, 1912.

Application filed November 30, 1910. Serial No. 594,928.

To all whom it may concern:

Be it known that I, LOUIS J. BALTZ, a citizen of the United States, and resident of Buffalo, in the county of Erie and State of New York, have invented new and useful Improvements in Suction-Tubes for Hydraulic Dredging-Machines, of which the following is a specification.

My invention relates to improvements in suction tubes for hydraulic dredging-machines, and more particularly to means within the tube for crushing rock and other solids drawn into the tube.

In hydraulic dredging-machines of certain types, a suitable digging or excavating implement is used for loosening soil and digging canals, trenches, etc.; and connected with such implement is a suction tube through which the material dug is caused to be drawn by a suitable pump.

This invention is particularly designed for digging material containing rocks or other solids and it has for its object the provision of a simple and effective crushing means within the suction tube for crushing the rocks or solids as they are drawn therethrough.

A further object of my invention is to provide a by-pass which connects with the main portion of the suction tube at opposite sides of the crushing means so that when loose material such as sand, gravel, loam or the like is dug by the digging implement, that portion of the suction tube containing the crushing means can be cut out so that the material will pass directly through the by-pass and to one side of the crushing means; also to provide suitable means for directing the material through the portion of the suction tube containing the crushing means or to the by-pass as may be found desirable.

Another object of my invention is the provision of a gyrating crusher-head surrounded by a crusher-shell and limited in its movement so as to occupy very little space within the suction tube.

With these and other objects in view, my invention consists in the construction, arrangement, and combination of parts to be hereinafter described and particularly pointed out in the subjoined claims.

Referring now to the drawings forming part of this specification, Figure 1 is a horizontal section through a portion of a suction tube showing my invention in a repre-

sentative form. Fig. 2 is an enlarged cross-section taken on line 2-2, Fig. 1. Fig. 3 is an enlarged longitudinal section taken on line 3-3, Fig. 1. Fig. 4 is an enlarged longitudinal section taken on line 4-4, Fig. 1. Fig. 5 is a cross section on a slightly reduced scale taken on line 5-5, Fig. 4. Fig. 6 is a cross section taken on line 6-6, Fig. 4. Fig. 7 is a cross section taken on line 7-7, Fig. 4.

The reference letter A designates a suction tube having a main passage B and a by-pass B¹. This tube in part comprises two oppositely disposed Y-shaped members A¹, A², one arm a of each Y-shaped member forming part of the by-pass, and the other arm a¹ forming part of the main passage. The arms a of the Y-shaped members are connected by a distance tube a², while the arms a¹ are connected by a crusher section or shell a³ in which my improved crushing apparatus C is located. One Y-shaped member may well be termed an "entrance member", and the other a "discharge member".

In the entrance member, designated A¹, is located a gate D pivotally secured therein at the crotch d and capable of swinging from the position shown in full lines, in Fig. 1, to that shown in dotted lines, or conversely. Pivotally secured to the discharge member designated A², is a gate d¹, its pivot point being also at the crotch of said member so that it may close the discharge end of the by-pass as shown in full lines, or the discharge end of the main passage as shown in dotted lines. These gates are secured to rock-shafts d² which pass out through stuffing boxes d³ in the upper wall of the tube at the crotches thereof and have operating levers d⁴ secured to their outer ends by means of which the gates may be swung either into position to close the main passage, or to close the by-pass, as desired. The outer ends of the Y-shaped members are secured to the usual tube-sections E.

The crusher section a³ is enlarged laterally and made preferably circular in a diagonal plane, with the axis thereof at an acute angle to the course of the material passing through said section. In order to withstand the crushing force, the circular portion of the crusher section or shell is made heavier, as at d⁵, and an internal endless depression is formed in this cylindrical wall to receive chilled iron staves F which provide a crusher lining for the shell and

which lining may be of chilled iron or any other hardened metal capable of withstanding the crushing strain or wear to which the internal surface of the crusher shell is necessarily subjected.

- 5 The crusher shell has extending therethrough a crusher shaft G which is arranged diagonally therein and one end of which enters a "floating" sleeve H located in an 10 opening H¹ formed in one of the lateral extensions of the shell; said opening being closed by a cap h secured to the outer side of said extension and said sleeve H being of smaller diameter than said opening so 15 as to permit of its oscillating therein, thus forming what I term a "floating" fulcrum for the shaft. A stuffing box I closes the inner end of the opening H¹, and in order to properly receive and support said stuffing box, the crusher shell is provided with an annular depression i around the shaft 20 G in which depression is mounted a gyrating stuffing-box plate i², itself having a depression to receive packing i³ held in 25 place by a gland i⁴. The stuffing-box plate i² is retained in the depression i by means of clips i⁵ fastened to the crusher shell, as at i⁶, and having their free ends extending over the marginal portion of said plate. 30 In line with the lining of the crusher-shell, the shaft G is flared rearward or toward the discharge end of the shell, as at g, and forced onto this flared portion of the shaft, is the crusher-head J which is 35 itself flared rearward. The enlarged cylindrical portion of the crusher-shell is tapered rearward so as to provide an annular crushing space K between the crusher-head J and the lining F; said space being gradually diminished rearward or toward the 40 discharge end of the crusher section so that rocks or other solids entering said section, will easily be drawn into the crushing space and when the crusher-head gyrates, as will 45 be presently described, the solids will be most effectively crushed and can then continue in their course through the suction tube and pump to be delivered at the desired point. 50 At a point diagonally opposite the opening H¹ the crusher-shell is provided with a comparatively large opening L which is closed by a bearing sleeve or casing L¹ whose inner end enters said opening, and 55 said bearing-sleeve or casing has an outstanding flange l near its inner end through which are passed bolts l² that take into the wall of the crusher section to securely fasten said bearing-sleeve or casing in position. Said bearing-sleeve or casing is 60 open at its outer end and provided with a removable cap l³ fastened thereto by means of bolts l⁴. In said bearing-sleeve or casing is located for rotation, an eccentric sleeve 65 M which is inserted through the open outer

end of said sleeve or casing when the cap l³ is removed and which has at its outer end a gear wheel m, preferably formed integrally therewith and provided with an axial boss m¹ on its outer flat face whose outer face is made convex; said boss entering a concaved depression m² formed on the inner side of the cap l³. The bearing-sleeve or casing L¹ is enlarged at its outer end beyond its intermediate dimensions to 70 accommodate the gear wheel m and at one point it is extended laterally, as at l⁵, to accommodate a pinion N in mesh with the gear wheel m and secured to a driving shaft N¹ journaled at one end in the sleeve or 75 casing, as at n, and passing through a stuffing-box formed in the cap l³. Said driving-shaft has a belt pulley O secured thereto and may be suitably journaled outside of the crusher section in any suitable 80 manner.

The crusher shaft G has its rear end loosely fitted into the eccentric sleeve M and between the crusher-head and said sleeve it is provided with a parti-spherical enlargement g¹, surrounding which is a stuffing-box P comprising a stuffing-box plate p having a packing depression p¹ in which packing is located and a gland p² entered into said packing-depression to compress 90 the packing around the parti-spherical portion of the shaft in a water-tight manner. The stuffing-box plate p bears against a wearing ring p³ fastened to the end of the bearing-sleeve or casing L¹ by means of 100 bolts p⁴; said wearing ring having an annular rib p⁵ to which are fastened clips p⁶ that overlap the marginal portion of the stuffing-box plate and retain the same in proper position against said wearing ring. 105

During the operation of the crushing apparatus, the rear end of the crusher-shaft, which is entered in the eccentric sleeve M, is caused to continually change its center and said shaft may rotate within the sleeve, 110 and under certain conditions does rotate within said sleeve with the latter rotating independently around it. Owing to the shaft being packed against leakage of water by the stuffing-boxes I and P, a certain amount of friction is created thereon, thus, when the eccentric sleeve rotates, there is under ordinary conditions, only a wabbling or gyrating movement of the shaft; and during such movement, the stuffing-boxes I and P are similarly moved, the stuffing-box P having a greater range of movement than the stuffing-box I. Owing to the rear end of the shaft having direct connection with the eccentric sleeve and the front end thereof being practically fulcrumed in the floating sleeve H, this action on the part of the crusher shaft is continued at all times except when a rock or other solid matter enters the crusher shell between the crusher- 130

head and the crusher lining, at which time considerable friction is created on the crusher-head which compels the shaft to rotate also.

5 Having thus described my invention, what I claim is,—

1. In an apparatus of the kind described, the combination of a suction tube having a main passage and a by-pass opening at opposite ends into said main passage, and a crusher in said main passage between the ends of said by-pass.

2. In an apparatus of the kind described, the combination of a suction tube having a main passage and a by-pass, a crusher in said main passage, and means for directing the material passing through said tube to said crusher or diverting the same through said by-pass.

20 3. In an apparatus of the kind described, the combination of a suction tube having a main passage and a by-pass connected at opposite ends with said main passage, a pivoted gate at each end of said by-pass, 25 and a crusher in the main passage between said gates.

4. In an apparatus of the kind described, a suction tube having a pair of Y-shaped sections, a distance section connecting two 30 arms of the Y-shaped sections, and a crusher section provided with crushing mechanism and connecting the other arms of said Y-shaped sections.

35 5. In an apparatus of the kind described, a suction tube having two Y-shaped sections, a gate provided to the crotch of each Y-shaped section so as to open or close either thereof, a distance section connecting

two arms of said Y-shaped sections, and a crusher section provided with crushing mechanism connecting the other arms of 40 said Y-shaped sections.

6. In an apparatus of the kind described, a suction tube having an enlarged circular portion, a crusher shaft arranged in said 45 circular portion, and a crusher-head mounted on said shaft and arranged to gyrate.

7. In an apparatus of the kind described, a suction tube having an enlarged circular portion, a crusher shaft arranged in said 50 circular portion, and a crusher head carried by said shaft and arranged for gyrating movement within the circular portion of said tube.

8. In an apparatus of the kind described, a suction tube having a circular enlarged portion with its axis at an angle to the course of the material passing through said tube, a shaft arranged therein, a crusher-head mounted on said shaft, and means for 60 imparting a gyrating movement to said shaft.

9. In an apparatus of the kind described, the combination of a suction tube having a main passage and a by-pass or auxiliary 65 passage opening at opposite ends into said main passage, and a crusher in one of said passages between the ends of the other passage.

In testimony whereof, I have affixed my 70 signature in the presence of two subscribing witnesses.

LOUIS J. BALZ.
